MEANS FOR MOUNTING MACHINE GUNS
IN AIRPLANESPaul H. Kemmer, Fairfield, and Carl E. Reichert
and Charles S. Butt, Jr., Dayton, Ohio

Application July 9, 1943, Serial No. 493,982

3 Claims. (Cl. 89—37.5)

(Granted under the act of March 3, 1883, as
amended April 30, 1928; 370 O. G. 757)

1

The invention described herein may be manufactured and used by or for Government for governmental purposes, without the payment to us of any royalty thereon.

This invention relates to means for mounting machine guns or rapid firing cannon in airplanes and its principal object is to increase the fire power and field of fire of airplanes without a proportionate increase in the number of guns and weight, so that heavy fire may be directed toward an enemy approaching from any angle whatever. Another object is to provide a gun mount and arrangement which may be readily adapted to known types of airplanes; and especially to the ends of the fuselages or the nacelles. A further object is to provide an airplane having turrets so located and shaped as to permit higher airplane speeds and longer ranges without loss in offensive or defensive fire power. A further object is to provide a turret whose outside contour is such that it blends into the fuselage without any break in the fairing lines. Other objects will appear from the following description of the preferred embodiment of the invention.

As disclosed in the Funk Patent No. 2,236,312 dated March 25, 1941, it is old to provide a rotatable turret at the nose of an airplane and to mount a machine gun in a ball joint carried on a slidtable panel which may move the gun longitudinally of the rotatable turret. Such an arrangement will permit an extreme elevation or traverse of perhaps 45° in either direction, or in other words will provide a field of fire which is approximately a cone with a vertex angle of not more than 90°. However, at and near the limits of movement of the machine gun it cannot be aimed accurately because of the position of the gunner. Furthermore, a cone of fire of 90° leaves a very large area above, below, to either side of and to the rear of the airplane which cannot be defended unless the airplane changes its course; and regardless of frequent changes in course an airplane armed as described in said patent will be nearly helpless if approached from the rear and above by a plane of equal or greater speed. As more fully explained in the periodical "Flight," issue of February 11, 1943, pp. 144, 145, the Messerschmitt 210 A-1 airplane has not only two fixed machine guns and two fixed cannon in the nose but also two rearwardly firing machine guns in two barbettes located on opposite sides of the fuselage about halfway between the nose and the tail, both barbette guns being sighted and remotely controlled by an electrical system operated by the rear gunner. These guns can be

2
elevated approximately 35° above or below center and can be traversed through approximately 39°. Obviously this airplane while formidably armed may be approached from many angles without encountering defensive fire. The famous B-17 ("Flying Fortress") bombers have no "blind spot"; but this is accomplished at the expense of many guns located in the turrets and barbettes which project from the fuselage at different points and materially reduce the speed and range of these bombers.

In accordance with the invention, a bomber or other airplane is provided with nose and tail turrets preferably at opposite ends of the fuselage, each housing one or more machine guns or rapid firing cannon, and these turrets are rotatable substantially about the longitudinal axis of the fuselage, while the machine guns are swingable on axes substantially at right angles to said longitudinal axis. The preferred arrangement permits the swinging of each machine gun or cannon through an arc of 226°, the result being that a single gun at the nose and another at the tail may together defend the entire field surrounding the airplane. Our invention also contemplates the location of guns at various other points as will be described.

In the accompanying drawings forming a part of this specification:

30 Fig. 1 is a diagram in plan showing a medium bomber in dot and dash lines equipped with nose and tail turrets embodying the invention, also indicating in full lines the fields of fire of the several sets of machine guns; the extent of projection of the machine guns being exaggerated;

Fig. 2 is a similar view but in side elevation;

Fig. 3 is a perspective view of one of the turrets with four machine guns, the view being partly diagrammatic and omitting the shield and many other details;

40 Fig. 4 is a view from the rear showing diagrammatically the arrangement of the ammunition cans, feed chutes, link ejection chutes and cartridge case ejection chutes relative to the machine guns;

Fig. 5 is a perspective view of a turret showing the machine guns in an extreme position;

Fig. 6 is a wiring diagram of one form of control means for the turret and guns, whereby the guns are aimed automatically by merely pointing an aiming device at the target;

Fig. 7 is a detail in section showing the rotary mounting of a turret on the fuselage, also the motor for rotating it; and

50 Figs. 8 and 9 are each diagrams in plan like Fig.

1, but showing modified arrangements of turrets on two different types of airplanes.

Referring particularly to the drawings, and first to Figs. 3, 4 and 5, each turret of the invention has a hood or shield 11 of an elongated cup-like form with a smooth outer surface and preferably made of sheets of "Plexiglas" (a transparent thermoplastic acrylic resin) united and reinforced in a conventional manner. Instead of "Plexiglas," other materials such as armor plate, aluminum, plywood or opaque plastics may be used, since it is not necessary to sight through the walls of the turret. The entire shield is removably secured at its rear end by studs 11a or the like (Fig. 7) to an annular frame 12 preferably made of some light metal such as magnesium alloy or Duralumin. Anti-friction bearings, for example, roller bearings 13a, 13b, may be carried on the outside of annular frame 12 and may roll in machined slots provided in a circular base ring 14 secured to the forward end of the fuselage 15 of the airplane. The general plane of base ring 14 is at right angles to the longitudinal axis of the airplane, so that the turret must rotate about said axis or about an axis parallel thereto. One or more machine guns 16, preferably four caliber .50, M2 Browning aircraft basic machine guns, preferably arranged in two pairs on either side of the medial plane of the turret, are enclosed by turret body 11 except for their muzzles which protrude through slots 17, 18 in the "Plexiglas." Slots 17, 18 are shown as extending parallel to each other from points near the secured end of the "Plexiglas" shield around the nose and back on the opposite side to points equally near said secured end. The length of the slots should be such as to permit traverse or elevation of the pairs of machine guns through a total angle of more than 180° and preferably of 226° as will be described. However, the slots need not be on diametrically opposite sides of the turret since the turret can be rotated in either direction through 360° to bring the slots (if confined to one side) to any desired angular position. If preferred, movable panels (not shown) may close the slots except where the machine guns project, thereby to reduce drag.

To make possible a traverse of 226° of each cannon or machine gun carried in the nose and tail turrets, a support 19 in the form of a hollow box or casing is rigidly secured at one end to the annular frame 12 to extend at right angles to the general plane of the annular frame. The hollow casing 19 provides a central longitudinal partition within the shield 11 dividing the turret into two compartments each containing a pair of machine guns 16. Supported centrally of the hollow casing 19 is a circular, hollow gun mount 20 to which the guns are rigidly secured by means not shown. Gun mount 20 may be rotatable but preferably is oscillatable through a total angle of 226° about an axis at right angles to the axis of rotation of the turret. A U-shaped frame having two parallel arms 21 joined by a straight shank 22 is pivoted as at 23 upon tie plates 24 each riveted or otherwise secured to the outer ends of three converging arms 25, 26, 27. These arms are secured at their other ends to frame 12 at widely spaced points for maximum rigidity. Thus the tie plates are rigidly supported parallel to each other and in turn may assist in supporting shield 11, which may be fastened by studs 28 and washers 29 (Fig. 5) outside of the tie plates. The U-shaped frame provides additional support or tying means, transmitting the load of the guns

and ammunition to annular frame 12, and has its shank 22 passing through the circular gun mount 20 to extend on opposite sides thereof. The ammunition cans 30, of which there is one for each machine gun, each containing several hundred rounds of ammunition on the usual disintegrating belts (not illustrated), are secured preferably to the U-shaped frame by means not shown. The ammunition cans 30 are arranged side by side, 10 to conserve space, which causes the lower machine gun of each pair to project about 6" beyond the muzzle of the other gun of the same pair. Each machine gun has a link chute 31 for discharge of the links of the disintegrating ammunition belt, and a shell case chute 33 for discharge 15 of the empty shells, both the links and shell cases moving first into the hollow gun mount 20 and then through the preferably open periphery of the gun mount to the interior of the hollow box or 20 casing 19. Thus the links and shell cases do not collect in the turret to interfere with rotation and traverse of the guns, or replacement of the ammunition cans. Ammunition blocks 34 and ammunition belts 35a, 35b are also indicated diagrammatically.

The axis of traverse or elevation of the machine guns 16 is obviously the axis of rotation of the gun mount 20 (which is also the axis of pivots 23); and this axis is far enough forward of the 30 plane of annular ring 12 to permit the guns to fire rearwardly to a certain extent, as well as forwardly, in all angular positions of the turret. The arrangement is preferably such that each 35 pair of machine guns in each turret may oscillate about the axis of pivots 23 through an angle of 226°. See Figs. 1 and 2. In other words, each 40 of the four machine guns in the preferred arrangement has a field of fire that is a spherical segment of one base, out of which a cone of revolution having a vertex angle of 134° has been carved. Expressing the matter otherwise, the machine guns each have a field of fire substantially equal to that portion of a sphere which is generated by the complete revolution of a circular sector (having a vertex angle of 113°) about the diameter of the circle of which the sector is 45 a part.

As indicated in the diagrams, Figs. 1 and 2, the fuselage 15 of the two engine bombardment plane extends well forward of the wings 36 and engine 50 nacelles 37 and with the pivot axis 23 of the guns located as described, the 226° arc through which the guns of the nose turret may fire will clear the tips of wings 36 while the field of fire of the 55 guns in the tail turret will clear the tail structure 38. As a projection of the lines indicating the arcs of fire will show, the two fields of fire of the nose and tail turrets intersect at points 60 closer to the fuselage longitudinal axis than the total span of the wings and at a distance but slightly exceeding the extreme overall length 65 of the bomber fuselage including the turrets. For example, if the total span of the wings is 114 ft. and the overall length of the fuselage including turrets is 79 ft. 3 in., the fields of fire of the nose and tail turrets will intersect at approximately 85 ft. 9 in. from the longitudinal axis of the fuselage. Hence the described bomber has eight machine guns which may hit an enemy 70 when very close and at any angle whatever, yet has no turrets or barbettes which will increase the drag.

To rotate each turret, an internal ring gear 39 (Figs. 3 and 7) is secured to the annular frame 75 12 and a reversible electric motor 40, controlled

by means to be described, drives a reduction gear train (not shown) in a casing 41, said gear train having a pinion 41a meshing with the ring gear 39 to drive it at the desired speed. To bring the ring gear, hence the turret, to a quick stop when power to motor 40 is shut off, a solenoid brake 42 (Fig. 6) of conventional construction may be employed. To point the guns 16 toward the target, a controller or aiming device 50 which may have the form of a pistol, is connected electrically with motor 40. The arrangement is such that any movement of the aiming device 50 (which may be located in the pilot's cabin or anywhere on the airplane) is faithfully reflected in corresponding movement of the guns 16. The control to be described is adapted from the Mittag expired Patent No. 1,547,435, dated July 28, 1925. While only the control for turret rotation is described in detail, the same control is used to effect elevation or traverse of the guns, or in other words, two duplicate electrical control systems are used, one acting responsive to movements of the aiming device about one axis, the other responding in the same manner to movements of the aiming device about an axis at right angles to the first axis. Thus the aiming device 50 causes sufficient rotation of the turret and traverse of the guns to make the guns aim in the direction in which the aiming device points. Firing is controlled by conventional means not shown.

A field winding 53 is rotatably mounted and driven by movement of the controller 50 about an axis parallel to the longitudinal axis of the plane, and is energized from the source of power S. Co-operatively associated with field winding 53 is a stationary polycircuit armature winding 54. Field winding 53 and armature winding 54 together constitute an inductive device which is sensitive to the position of the controller and which sends out electrical impulses to a second inductive device including a winding 55 which is rotatably mounted, and a three phase armature winding 56. The described inductive devices produce an alternating E. M. F. which has a value substantially proportional to the angular disagreement or variance between the controller or pointer 50 and the guns and which has a direction relative to the alternating current supply source that is determined by the direction of this disagreement. The guns are moved about the axis of frame 12 by motor 40 which is an A. C. motor controlled in response to the voltage induced in winding 55. Motor 40 is shown as a three phase induction motor having a Y connected three phase winding 57 and squirrel cage rotor winding (not indicated) which has sufficient resistance so that the motor will not run as a single phase induction motor.

For the control of motor 40 the E. M. F. induced in winding 55 (when there is angular variance between the controller and the guns) is impressed upon the input or grid circuits of two electron discharge amplifying tubes 60 and 61 shown as of the three electrode type. This connection is preferably effected through a transformer 62 the secondary 63 of which is provided with a central tap 64 so that one-half of the secondary 63 is connected in the input or grid circuit of tube 60 while the other half is connected in the input or grid circuit of tube 61. To improve the operation, condensers 65, 66 are connected across sections of the secondary. The output or plate circuits of the tubes are connected to the two halves of the primary 69 of transformer 70. Tubes 60, 61 are thus connected to a push-pull

or two wave circuit so as to reproduce both halves of the E. M. F. wave induced in winding 55 and thus impress an A. C. on transformer 70. Tubes 60, 61 amplify the power output of winding 55.

For further amplification the secondary 71 of transformer 70 is provided with a central tap 73 and its two halves are connected in the input or grid circuits of two electron tubes 74, 75, the output or plate circuits of which are connected to the two halves of the primary 78 of a transformer 79. Tubes 74, 75 are connected in push-pull or two wave circuits in the same manner as tubes 60, 61, their function being to amplify the output of the two latter tubes. As thus arranged, the winding 55 supplies only the very slight amount of power required to energize the input circuits of tubes 60, 61.

The secondary 80 of transformer 79 is provided with a central tap 81 which is connected through a conductor 82 to one side of the A. C. supply S, the opposite side of the supply source being connected to one terminal 83 of motor winding 57. The other terminals 84, 85, of said motor winding are connected to the terminals of secondary 80. This connection of transformer 79 is similar to the well known Scott transformer connection for converting two phase to three phase power. It has been found that the power output from the electron tube amplifying devices has quite a large phase displacement with respect to the A. C. supply S. This power output having one direction is impressed on the secondary 80, the terminals of which are connected to two of the motor winding terminals while the source of supply S corresponds to the teaser coil of the Scott connection and is connected in central tap 81 to the remaining motor winding terminal. This system of connections gives an approximately three phase source of supply for motor 40.

In the operation of the system, when the winding 55 is at right angles to winding 53 as illustrated in the drawing, corresponding to a condition of angular agreement between the controller and the guns, no voltage is induced in winding 55 and consequently no power is supplied to motor 40. The single phase current from source S will have no effect in causing rotation of the motor. Now assuming that the controller is moved in one direction, a voltage will be induced in winding 55 which will result in power being supplied from the amplifying devices to motor 40 causing rotation of the motor to move the turret until the guns are moved into angular agreement or parallelism with the controller.

Since the voltage induced in winding 55 depends on the amount of the angular variance or disagreement, the power supplied to the motor will likewise depend upon the amount of the angular disagreement. When the guns point exactly in the same direction as the controller the three phase power is cut off from the motor and it immediately stops. In case the controller is moved in the opposite direction, it will be observed that since the voltage induced in winding 55 is in the opposite direction, that is, displaced 180° in phase, the power supplied to terminals 84, 85 will be reversed in polarity, so that rotation of the motor will be reversed and the guns will therefore be moved in the proper direction to follow the controller.

To elevate and lower or traverse the guns, a motor 86 (like motor 40, see Fig. 3) drives a pinion 87 through a reduction gear in box 88, said pinion meshing with a segmental annular gear 89 secured to one side of the casing 19 and surround-

ing the gun mount 20. Annular gear 89 may subtend an angle of slightly more than 226°, since its function is to effect oscillation of the gun mount 20 through said angle (or any smaller angle desired) when the motor 86 is energized. Motor 86 is conveniently mounted on the shank 22 and is controlled through a circuit exactly like the one illustrated in Fig. 6, hence not shown. The controller or aiming device 50 is elevated and lowered at the will of the gunner, and the gun mount 20 will swing the machine guns through exactly the same angle.

In Figs. 1 and 2 an additional pair of machine guns 90 are shown as carried within the fuselage on each side thereof to increase the fire power of the bomber especially if attack comes simultaneously from several different hostile aircraft. The preferred arrangement is to mount each pair of guns on a cylindrical carrier member 91 supported on bearings (not shown) carried inside the fuselage so as to rotate about a transverse axis at right angles to the longitudinal axis of the airplane. Preferably each pair of guns 90 is directly opposite the other pair and besides the described angular movement each pair of guns may swing through a total angle of about 130° about an axis at right angles to the axis of revolution of the carrier 91. However, a minimum total traverse of 90° is considered to be within the scope of the invention. By known mechanisms, either the fire may be discontinued automatically when the angles of these guns are such as to point at some part of the plane they are carried on, or else the guns are automatically forced to travel in a path which prevents shooting at said plane. The cylindrical carrier members 91 are wholly inside the bomber fuselage so that there are no projecting parts except portions of the gun barrels. The gun swinging and rotating mechanisms may be similar to those described. Members of the bomber's crew may crawl beneath or over the carriers 91, which are end to end, in the event it is necessary to pass from the tail to the nose of the plane, or vice versa. Window panels 92 are on opposite sides of the carrier mounts so as to give a good field of vision for aiming these side guns. The described arrangement will permit the gunners to bring the fire of ten machine guns, or several cannon plus machine guns, on either side of and at many angles above and below the bomber.

In Fig. 8 we show an arrangement wherein the airplane 95 has our turrets on each nacelle after body 96, and also on the forward portion of a pusher type nacelle 97. Fig. 9 shows the turrets on the forward and after portions of the central body 98 of a twin boom type of airplane 99. A single turret at either end may be used. These two views also exaggerate the extent of projection of the machine guns.

While the described turrets enclose the ammunition cans, it is within the scope of the present invention to locate them to the rear of the main supporting ring 14, i. e., within the fuselage, the cans then rotating with the annular frame 12. Belt feeds of known construction would carry the ammunition belts from the several cans to the machine guns. This modification would be advantageous in that the turrets could be smaller, the ammunition capacity would be materially increased, and the removal of empty cans and replacement with full ones would be facilitated. However, no claim is made to this specifically.

While we have described our invention as embodied in a concrete form and as operating in a specific manner, it should be understood that we

do not limit the invention to the described matter since various modifications will suggest themselves to those skilled in the art without departing from the spirit of the invention.

Having described an embodiment of our invention, what we claim as new and desire to secure by Letters Patent of the United States is:

1. A gun turret structure having a field of fire covering a spherical sector with a vertex angle greater than 180° for use on opposite outboard positions of an aircraft to provide a complete sphere of fire about the aircraft comprising; an annular base member adapted to be secured to an aircraft structure; a cup-shaped turret member having an axis of revolution passing concentrically through an open end thereof, said turret member adjacent its open end and said annular base member being juxtaposed in relatively movable concentric relation wherein said turret member may rotate about said axis of revolution throughout 360°; operator-controlled power actuated means operatively associated with said cup-shaped turret and annular base members to power rotate said cup-shaped turret member; a U-shaped gun mount journaled at the ends thereof within said cup-shaped turret member rotatable about an axis perpendicular to said cup-shaped turret member axis of revolution through an angle greater than 180°; a turret support having a circular opening therein concentric to said gun mount axis in which the closed portion of said U-shaped gun mount is operable in an arc in close relation to the periphery of said circular opening; gun means mounted on said gun mount to point substantially radially outward from said gun mount axis of rotation, said cup-shaped turret member having slots therein through which said gun means are operative; and operator-controlled power actuated means operatively associated with said turret support and said U-shaped gun mount to power rotate said gun mount about its axis whereby said gun means are actuatable to be directed throughout a spherical field of fire greater than a hemisphere.

2. A gun turret structure having a field of fire covering a spherical sector with a vertex angle greater than 180° for use at opposite stations of an aircraft to provide a complete sphere of fire about the aircraft comprising; an annular base member adapted to be secured to an aircraft structure; an annular turret member having journal means extending from one plane thereof to provide a journal axis parallel to a diameter of said annular turret member, said annular turret member being journaled to said annular base member along the annular portion thereof to rotate 360° about an axis of revolution common to both said annular members; a gun mount having trunnions journaled in said journal means; a turret support fixed to said annular turret member and extending laterally therefrom on the same side as said journal means having a circular opening therein with the center thereof lying on said journal axis; operator-controlled power means operatively associated with said gun mount and said turret support for rotating said gun mount in excess of 180° about said journal axis and operator-controlled power means operatively associated with said annular base and annular turret members for rotating said annular turret member throughout 360° with respect to said annular base member; guns mounted in said gun mount pointing substantially radially outward from said journal means axis; and a gun turret cover enclosing said gun turret structure

having slots therein through which said guns fire and being supported on said annular turret and turret support members whereby said guns can be pointed in any direction in a spherical field of fire greater than a hemisphere.

3. A gun turret structure for aircraft comprising; an annular base ring adapted to be secured to an aircraft structure; and elongated cup-like turret member having an axis of revolution passing concentrically through an open end thereof, said turret member adjacent its open end and said annular base ring juxtaposed in relatively movable concentric relation wherein said turret member may rotate about said axis of revolution through an angle of 360°; an internal ring gear attached to said turret member adjacent to and in the plane of the open end thereof; operator-controlled power-actuated means in fixed relation to said annular base ring operative to rotate a pinion gear operatively associated with said internal ring gear; a gun mount journaled within said cup-like turret member rotatable about an axis perpendicular to said cup-like turret member axis of revolution; an internal segmental ring gear subtending an angle of at least 226° connected to said cup-like turret member in operative association with an operator-controlled power-actuated pinion gear fixed for operation relative to said gun mount for rotating said gun mount substantially in excess of 180° about its axis; and at least one gun fixed to said gun mount to point radially outward from said gun mount axis of rotation for firing through a slot in said turret member whereby said gun is adapted to have a field of fire substantially equal to a spherical sector generated by a complete revolution of a circular sector having a vertex angle of at least 113° about the diameter of the circle of which the sector is a part.
